P. R. GLASS

TRIMMING APPARATUS

Filed Feb. 23, 1921

Patented July 28, 1925.

1,547,318

UNITED STATES PATENT OFFICE.

PERLEY R. GLASS, OF WAYLAND, MASSACHUSETTS, ASSIGNOR TO UNITED SHOE MACHINERY CORPORATION, OF PATERSON, NEW JERSEY, A CORPORATION OF NEW JERSEY.

TRIMMING APPARATUS.

Application filed February 23, 1921. Serial No. 447,081.

To all whom it may concern:

Be it known that I, PERLEY R. GLASS, a citizen of the United States, and resident of Wayland, in the county of Middlesex and

5 State of Massachusetts, have invented certain Improvements in Trimming Apparatus, of which the following description, in connection with the accompanying drawings, is a specification, like reference characters 10 on the drawings indicating like parts in the several figures.

This invention relates to trimming apparatus, and is illustrated as embodied in a device for trimming the covers of heels which are 15 attached to shoes.

According to one process of manufacturing shoes with covered heels, the heels are attached to the shoes before the heels are covered. The cover blanks are then attached to the heels with surplus cover material projecting above the tops or heel seat faces of the heels and overlapping the shoe upper. This projecting surplus material of each heel cover is then trimmed, to leave 20 a margin of a suitable width to be tucked into the rand crease. Thereafter the part 25 of the cover which projects below the bottom or tread surface of the heel may be folded in and held by fastening a top-lift thereover.

30 An object of this invention is to improve trimming apparatus of a type suitable for trimming heel covers to remove the surplus material above referred to. To this end, the illustrated construction comprises co- 35 operating shear members, of which one may be stationary and the other reciprocable, and a gage or guide to direct the covered heel past the shear members. A feature of the invention is to be found in the use of a 40 stationary shear member having a projection which engages the heel at the rand crease, to prevent leaving a margin of less width than the minimum which can be 45 tucked into the rand crease. Another feature is the use of a gage or guide comprising an adjustable clamp, and a novel guide portion connected thereto by a spring.

50 Other features are to be found in various combinations and specific constructions which are pointed out in the appended claims, and which are shown in the accompanying drawings, in which

55 Fig. 1 is a perspective, partly broken away, of a heel-covering machine comprising my improved trimming apparatus;

Fig. 2 is cross-section of the apparatus, with a shoe in co-operative relation thereto;

Fig. 3 is a perspective of the stationary shear member; and

Fig. 4 is a perspective of the guide or 60 gage.

In the illustrated machine, an upright 10 is vertically adjustable in a base standard 12. From this upright project three arms 14, 16 and 18. Upon a bracket 20 carried by 65 arm 14 is a work preparing member 26, held on a rotatable spindle 22 by a screw 24. This member is used to open the rand crease before the cover is applied, to prepare it for tucking in the margin of the cover; and after 70 the cover is applied to the heel, it is again used to press the covering somewhat into the rand crease, to form a crease or mark in the cover which may be followed in 75 trimming the heel covering.

A main drive shaft is rotated from any convenient source of power by a belt acting on the pulley 36. Suitable connections from this shaft rotate the spindle 22 carrying the work-preparing member 26. Carried at the 80 right-hand extremity of the main drive shaft is a beating member 42, which may be used to pound and smooth the heel preparatory to placing the covering upon it.

At the forward end of arm 18 is a trans- 85 verse extension 52 in which is journaled a shaft 54, driven by belt 56. At the left-hand end of this extension is the trimming apparatus in which my invention is shown as embodied, and which is further described 90 below. By the use of this apparatus, the surplus covering material is removed, leaving a margin to be tucked into the rand crease by the tucking mechanism shown at 120, 134. Thereafter the covered heel is 95 smoothed by a finishing tool 150.

All of the foregoing parts, with the exception of the trimming apparatus, may be the same as parts bearing the same reference characters as shown in United States Letters 100 Patent No. 1,448,738, granted March 20, 1923, on my application filed Sept. 9, 1918, and for that reason will not be described herein.

The trimming apparatus comprises a 105 stationary shear member 70, a reciprocable shear member 58, and a gage or guide 74. The stationary shear member is shown in detail in Fig. 3. It comprises a work supporting portion 68, a cutting edge 66, and 110

a surface 64 to guide the severed material away from the apparatus. At 65 is shown a projection, just in advance of the cutting edge, which has the double function of supporting that portion of the heel-covering next to be cut, and of forming a minimum-width gage to contact with the heel, in the rand crease, when the margin left by the trimming is just sufficient to tuck into the 10 rand crease.

The reciprocable shear member 58 slides in ways in the casing, to insure rectilinear motion, and carries a cutting portion 59 at its lower end by a screw-and-slot connection 15 60, which permits of adjustment as the portion 59 is ground away in sharpening. The shear is reciprocated by a slide 61 and an eccentric pin or crank 62, and is held in position by a cover plate 63.

20 The guide 74 comprises a clamp 76, which surrounds extension 52 and may be moved back and forth thereon to vary the width of margin left on the heel cover to be tucked into the rand crease. In a channel 78 in the 25 clamp there is a slide 80, which carries a guide roller 82 arranged to follow the crease or mark in the heel covering over the rand crease. The clamp 76 and slide 80 are connected by a spring 84, which tends to push them apart. The slide 80 bears a pin 86, 30 which is engaged by a limiting slot 88 in a plate 90. The plate 90 is secured to the clamp 76 by screw-and-slot connections 92, which permit adjustment of the limiting positions of pin 86, and therefore slide 80, 35 relatively to clamp 76.

It will be noted that the guide roll 82, and the work-supporting portion 68 of the 40 stationary shear member 70, are so formed and arranged that they conform to the contour of a shoe, and do not tend to disturb the heel covering by lifting it away from the shoe as it is trimmed.

45 It will be obvious that variation in the form and arrangement of parts is feasible, and while one embodiment of my invention has been described in detail, it is not the intention to limit its scope thereby.

Having described my invention what I 50 claim as new and desire to secure by Letters Patent of the United States is:

1. In an apparatus for trimming the covers of heels attached to shoes, in combination, co-operating shear members to sever the heel covers to remove surplus cover material which overlies the shoe uppers, and a guide to ride in the rand crease of the shoe, the guide being adjustable with reference to 55 said members to vary the width of the margin left after trimming to be tucked into the rand crease.

2. An apparatus for trimming off the 60 surplus material of heel coverings which project above the tops of the heels attached to shoes and closely overlie the shoe uppers

comprising, in combination, a shoe guide, a stationary shear member having a thin portion shaped to conform to the contour of the shoe upper adjacent to the heel and adapted to be inserted between the shoe upper and the overlying surplus material of the heel covering to support said material without distorting it, and a shear member reciprocable in a direction normal to said portion and to the surface of a shoe 75 guided by said guide for co-operating with the stationary shear member.

3. In an apparatus for trimming off the surplus material of heel covers which project above the tops of heels attached to 80 shoes, in combination, a movable shear member, a stationary shear member to co-operate therewith in trimming the covers and having a projection to engage the heels to insure leaving tucking margins of at least 85 a minimum width, and a guide to follow creases in the covers over the rand creases of the shoes, adjustable to vary the width of the tucking margins.

4. In an apparatus for trimming the covers of heels attached to shoes, in combination, trimming means for removing surplus cover material which overlies the shoe uppers, an adjustable margin gage, and a 90 minimum margin-width gage.

5. In an apparatus for trimming the covers of heels attached to shoes to remove the surplus cover material which projects above the tops of the heels, in combination, a movable shear member, a stationary shear member having a cover-supporting portion, and a rand-crease guide, said guide and the cover-supporting portion of the shear member being formed and arranged to conform 100 to the contour of a shoe, to avoid distorting the cover as it is trimmed by forcing it outwardly from the shoe.

6. In an apparatus for trimming the covers of heels attached to shoes to remove the surplus cover material which projects above the tops of the heels, in combination, heel-cover trimming means, a gage device comprising a clamp movable to vary the position of heels relatively to said means, a guide to follow a crease in the heel cover immediately over the rand crease, and a spring connection between the clamp and the guide.

7. In an apparatus for trimming the covers of heels attached to shoes to remove the surplus cover material which projects above the tops of the heels, in combination, heel-cover trimming means, a gage device comprising a clamp movable to vary the position of heels relatively to said means, and a roller guide to follow a crease in the heel-cover immediately over the rand crease of the shoe.

8. In an apparatus for trimming the covers of heels attached to shoes to remove the 120

- surplus cover material which projects above the tops of the heels, in combination, a stationary shear member having a work-supporting portion and a cutting edge, a reciprocating shear member to co-operate therewith in trimming heel covers, and a rand-crease guide on the opposite side of the reciprocating shear member from the stationary shear member.
- 5 9. In an apparatus for trimming heel covers, in combination, a reciprocating shear member having a cutting edge, and a stationary shear member having a cutting edge to co-operate therewith to remove surplus cover material projecting above the tops of the heels and having a projection in advance of the cutting edge to support the portion of the cover next to be cut and also to act as a gage to prevent leaving a margin of less than 20 minimum width.
- 10 10. In an apparatus for trimming the covers of heels attached to shoes to remove the surplus cover material which projects above the tops of the heels, a stationary shear member having a cutting edge, a guide surface adjacent thereto for the surplus material, and a work supporting projection in advance of the cutting edge, in combination with a reciprocating shear member having a cutting edge to co-operate with the stationary cutting edge to trim the heel covers.
- 15 11. In an apparatus for operating on heels attached to shoes, a guiding device comprising a clamp which may be moved to change the position of a heel guided by the device, said clamp having a channel formed therein, a gage reciprocable in said channel and having a pin in the outer surface thereof, a spring in said channel and tending to push 25 the gage therefrom, and an adjustable plate to engage said pin to limit the movement of said gage.
- 20 12. In an apparatus for operating on heels attached to shoes, a guiding device comprising a movable clamp, a guide roll to ride 30 progressively in the rand crease, and a spring connection between said clamp and said roll permitting the roll to yield in a plane substantially perpendicular to its axis.
- 35 13. In an apparatus for trimming the margins of heel coverings which project above the tops of heels attached to shoes and closely overlap the shoe uppers, in combination, co-operating shear members for engaging opposite sides of the overlapping margins 35 of the heel coverings, means for effecting relative reciprocation of the shear members, a guide to ride in the rand crease of the shoe, the guide being adjustable relatively to the shear members to vary the width of the margin left after trimming, and a mounting for the guide adapting the guide to yield, in a direction parallel to the plane of relative reciprocation of the shear members.
- 40 14. In a trimming apparatus, a stationary shear member comprising a portion to be inserted beneath the edge of a covering on an attached heel, a surface to guide away the surplus covering material as it is trimmed, a cutting edge adjacent to the guiding 45 surface, and a projection in advance of the cutting edge to support the material next to be cut and to engage the rand crease as a gage determining the minimum width of covering to be left by the trimming operation.
- 45 15. In a trimming apparatus, a stationary shear member having a portion to be inserted beneath the work without disturbing it to support the work, a shoe guide arranged to 50 engage the work at the side opposite that engaged by the stationary shear member to determine the location of the trimming cut, and a movable shear member to co-operate with the stationary shear member and reciprocable in a direction normal to said portion and to the surface of a shoe guided by said guide.
- 55 In testimony whereof I have signed my name to this specification.

PERLEY R. GLASS.
